DISTILLATION OF WATER - IMMISCIBLE SOLVENTS FROM PROTEINACEOUS RESIDUES

Harold F. Saunders, Shaker Heights, and Harold F. Larson, Cleveland, Ohio, assignors to The Sherwin-Williams Co., Cleveland, Ohio, a corporation of Ohio

Application September 22, 1947, Serial No. 775,500

11 Claims. (Cl. 202—70)

1

This invention relates to improved methods for removing solvent from solvent-wetted vegetable residues, such as those remaining after solvent extraction of oils and fatty materials from oil-containing vegetable materials, and for the production of proteinaceous materials derived from such solvent-wetted residues.

The oil-containing vegetable materials may be seeds, beans, nuts and leaves containing proteinaceous material and oil, such as cottonseed, castor beans, soya beans, peanuts, flaxseed, hempseed, sunflower seed, pitacia nut, tungnut, coconut, carnauba leaves, and the like.

Processes for extracting oils from vegetable materials with volatile organic solvents leave insoluble solvent-wetted residues. These residues comprise cellular material, proteins, carbohydrates such as sugars, mucilages, and a small proportion of water, in more or less finely divided particles which may range in size from those of colloidal dimensions to a quarter inch or more. If the cortex or shell was not initially removed, it will also be present in the residue.

Heretofore, recovery of solvent from the residues for reuse in the extraction step has been effected by directly heating the solvent-wetted residues alone to volatilize the solvent. The solvents with which the residues are wetted are oil-miscible organic liquids or mixtures thereof. Such solvents normally have boiling points under standard conditions of from about 35° C. to about 100° C., and when in admixture with water under a partial vacuum, will vaporize at temperatures below about 60° C. Examples of such solvents are aliphatic hydrocarbons such as hexane and heptane and their isomers, and halogenated derivatives thereof, aromatic hydrocarbons such as benzene and mixtures of such compounds. To obtain the advantages of the present process the solvent must have a boiling point, at subatmospheric pressure, lower than the boiling point of water at the same subatmospheric pressure. Although the solvents usually have boiling points considerably below 100° C., it was generally necessary to employ temperatures above about 120° C. in order to achieve rapid and complete removal of the solvent from the residues.

The use of such high temperatures often results in charring or degradation of the residues including the proteinaceous materials, particularly when water is present in the residues as it usually is. These adverse effects often make it difficult or impossible to disperse the proteinaceous materials in acidic, salt or alkaline solutions as is often desirable to form suspensions or emulsions useful

2

in paints, coating materials, adhesives, etc. The practices heretofore employed in changing the solvent-wetted residues into water-wetted products have involved an intermediate drying operation which reduces their dispersibility or solubility in water.

It is an object of the present invention to provide methods for removing solvent from solvent-wetted vegetable residues without using high temperatures or prolonged heating periods which are normally required for removing solvent from the residues by direct heating.

It is a further object of this invention to transform the solvent-wetted residue to a water-wetted product without passing the material through an intermediate dry stage, so that the dispersibility or solubility of the product is unimpaired.

It is a further object of this invention to provide a continuous method of solvent removal and/or recovery, wherein solvent-wetted residues are continuously subjected to conditions which cause vaporization of solvent.

According to the present invention, a mixture of an aqueous liquid and a solvent-wetted vegetable residue is continuously introduced into a desolvantizing zone in which a mass of such mixture is maintained under conditions which cause evaporation of the solvent. A mixture of aqueous liquid, residues which still contain solvent, and water-wet, solvent-free residues is withdrawn from the desolvantizing zone. The solvent-free residues are separated from the solvent-wet residues by virtue of the differences in wetting and/or floating characteristics of the residues caused by the removal of the solvent from some of the residues. The solvent-wet residues are recycled to the desolvantizing zone for further treatment. The water-wet, solvent-free residues and aqueous liquid associated therewith are withdrawn from the system. In order to maintain continuous and efficient operation, the amount of original mixture of solvent-wetted residues and aqueous liquid introduced to the system should be substantially equal to the amount of water-wet, solvent-free residues and aqueous liquid which are withdrawn from the system.

The withdrawn water-wet residues may be used as such or may be further treated as described, for example, in the copending application Serial No. 773,481 of Harold F. Saunders.

The use of an aqueous liquid with the solvent-wetted residues provides several important advantages for removal of the solvent. The liquid causes greater dispersion of the residues and, hence, permits more ready vaporization of the

solvent. It enables the use of lower temperatures, thus avoiding and reducing the harmful effects on the residues. It also solubilizes proteinaceous materials and facilitates their extraction from the residues.

While such advantages are provided by the aqueous liquid even if it is water, a neutral salt solution or an acidic solution, exceptional advantages along these lines are provided if the aqueous liquid is alkaline. Such a liquid inhibits, to a large extent, the coagulation of heat-coagulable proteinaceous material during the solvent removal step.

The aqueous liquid may be mixed with the solvent-wetted residues by merely adding the water or solution directly while stirring or by adding water first and then the salt or acid or alkaline material, either in a dry state or in the form of a concentrated solution until the desired pH is obtained. Generally sufficient water is added to make an easily flowable slurry. When the residue contains a considerable quantity of mucilages, as in the case of flaxseed residues, more water is necessary than when a smaller quantity of mucilages is present as with soya bean, peanut and cottonseed residues.

The quantity and nature of the aqueous liquid and the particular pH values of the mixture is determined largely by the type of final products desired and the type of after-treatment to be given the water-wetted residues. These factors are fully described in the above-mentioned application of Harold F. Saunders, Serial No. 773,481.

In the mixture containing the aqueous liquid, solvent, and solvent-wetted residues, the solids are preferentially wetted by the solvent, and tend to float with the solvent on the aqueous liquid. In this state, the mixture is filterable only with difficulty, if at all, and resists separation by centrifuging, since the solids tend to flow off with the liquid. As the solvent is removed, the solids in the mixture become preferentially wetted by water and begin to settle in the aqueous liquid. After this change in wetting of the solids occurs, they can be readily separated from the mixture by filtration, settling or centrifuging.

According to the present method the mixture of solvent-wetted residues and the aqueous liquid is subjected to mild heat under a partial vacuum, preferably while its surface is being agitated and splashed to enlarge the surface and thereby facilitate evaporation of solvent therefrom. This may be accomplished in various ways, as by continuously introducing the mixture into the top of a vessel and letting it fall or spraying it onto an accumulation of the mixture in the bottom of the vessel. The surface of the mixture may also be enlarged by flowing the mixture over baffles. If desired, a stirrer may be provided in the bottom of the vessel to keep the accumulated mixture agitated sufficiently to prevent excessive setting of solid material. The evaporation of solvent is carried out at a subatmospheric pressure of about 28 inches and at a temperature between the boiling points of the solvent and water at the pressure employed. The mixture is then withdrawn from the vessel and a portion recycled to the top of the vessel. The remaining portion of the partially desolventized mixture is passed to a separator such as a settling tank or the like. As stated above, during the removal of the solvent, at least a portion of the residue becomes wetted with water and will settle in the aqueous liquid while that portion of the residue which remains wetted with solvent will float upon the

aqueous liquid. Therefore, when the mixture has been subjected to the conditions for solvent removal and a portion thereof transferred to a separator, the solvent-free, water-wetted residue is easily separable from the remaining solvent-wetted residue which can be recycled to the desolventizing vessel for further treatment with additional fresh mixture and with the unseparated portion of the mixture.

With reference to the drawing, which is a diagrammatic flow sheet of a system for carrying out the present invention, the solvent-wetted residues from an oil extraction operation are introduced through line 11 to a mixer 12 where the residues are rapidly stirred while an aqueous liquid is introduced through line 13 and mixed therewith. If desired, water may be introduced through line 13 and a concentrated alkaline solution may be added through line 13a. When the resulting mixture has the desired pH, it is passed continuously through line 14 to the top of a desolventizing vessel 15. This vessel is maintained at the desired temperature by any conventional means (not shown in the drawing) which may comprise a jacket surrounding the vessel through which a heating medium may be circulated or heating coils so situated that substantially constant temperature throughout the vessel will be maintained.

As illustrated in the drawing, the mixture which is introduced through line 14 is sprayed onto a pool of the mixture which is provided in the bottom of the vessel 15. The solvent vapors which are liberated in the vessel 15 are withdrawn through line 16. Line 16 is connected to a vacuum pump (not shown) so that the vessel 15 is maintained at a sub-atmospheric pressure of about 28 inches. The solvent vapors which are withdrawn through line 16 can be condensed, separated from any water present and recycled to the oil extraction stage.

A substantial proportion of solvent will be removed from the mixture in the desolventizing vessel 15 and consequently a large quantity of the solvent-wetted residues will become water-wetted. A portion of this mixture is then recycled from the bottom of the vessel 15 through a line 17 to line 14 and reintroduced into vessel 15 along with additional fresh mixture. The remaining portion of the mixture is passed through line 18 to a settling tank 19 where it is permitted to stratify.

That portion of partially desolventized mixture from vessel 15 which is recycled through line 17 to line 14 may vary from about 10% to about 95% of the mixture withdrawn from the vessel depending on various conditions. For example, it is desired to effect a high degree of splashing in the vessel 15 in order to more efficiently evaporate the solvent. This requires a relatively large volume of mixture as well as rapid flow through the vessel. If only freshly prepared mixture were introduced in large volume, the degree of desolventizing would be low since the mixture would be subjected to the splashing action for only a short period of time. It is therefore generally desirable to recycle from about 50% to about 90% of the partially desolventized mixture to the top of the vessel 15.

On the other hand, when a very low pressure is maintained and separate means for agitating the mixture are provided in the vessel, it is sometimes possible to obtain satisfactory desolventization even when only about 10% of the partially

5

desolventized mixture is recycled through lines 17 and 14.

In the settling tank 19 the remaining portion of mixture stratifies and the lighter or upper layer will comprise the remaining solvent-wetted residue and some of the aqueous liquid and is withdrawn through line 20 and recycled to the top of the vessel 15 for further evaporation of solvent. The lower layer which comprises aqueous liquid and the water-wetted residue is withdrawn through line 21. This material may be further treated in accordance with the process described in the above-mentioned application Serial No. 773,481.

Instead of withdrawing the aqueous liquid and water-wetted residue from the system through line 21, it may be passed through line 22, to a separator 23 for separation of liquids from solids. This may be accomplished by means of conventional filters, centrifuges or the like. The aqueous liquid is withdrawn through line 24 for additional treatment if desired, as mentioned in the aforesaid application Serial No. 773,481, while the solids, which are still moist with aqueous liquid, can be withdrawn through line 25 for use as such.

The settling tank 19 may, if desired, be maintained at subatmospheric pressure as is the desolventizing vessel 15. This may be accomplished by means of line 26 which connects the settling tank 19 with line 16. Under these circumstances any solvent vapors which are liberated in the settling tank may be returned to the solvent vapor line 16 for subsequent condensation and reuse.

Various conventional elements have been omitted from the drawings for the sake of simplicity, but it would be obvious to one skilled in the art that various valves, metering devices, temperature control and indication devices, pressure indicators, pH indicators, pumps, and the like can be used without departing from the spirit of the present invention.

According to the present invention, a vegetable residue wetted with an organic solvent, for example a residue from a heptane oil-extraction operation, is mixed in mixer 12 with water and a concentrated alkaline solution such as caustic soda, potash, ammonium hydroxide or the like, until a pH value of from about 8 to about 11 is attained. This pH value affords substantially complete solubilization of the alkali-soluble proteins although a pH value of from about 7 to 9 also gives satisfactory results. The quantity of water added is from about 10 to about 50 parts by weight to 1 part by weight of protein but in any event an amount capable of forming a freely flowing slurry should be added. During the mixing, the materials are constantly and rapidly stirred to prevent lumping and agglomeration.

This mixture is then passed through line 14 to vessel 15 which is maintained at a temperature of from about 35° C. to about 40° C. and at a subatmospheric pressure of about 28 inches. As the mixture falls to the bottom of the vessel 15, a substantial quantity of the heptane is evaporated and withdrawn through line 16.

A portion of the mixture is recycled to vessel 15 while the remaining mixture is passed to settling tank 19 for separation of the aqueous phase containing the water-wetted residues from the phase containing the heptane-wetted residues and some of the aqueous liquid. The last-mentioned phase is recycled through line 20 to the vessel 15 for further evaporation of heptane along with additional fresh mixture and the re-

6

cycled portion mentioned above. The lower, or aqueous phase, is withdrawn through line 21 and may be used as such or may be treated further in accordance with the process described in application Serial No. 773,481. On the other hand, the aqueous phase may be further separated in the separator 23 to obtain a moist solid material and an aqueous liquid substantially free of solids. The liquid can be further treated while the solids may be used as such.

What is claimed is:

1. A continuous method for treating vegetable residues wetted with a substantially water-insoluble organic solvent having a lower boiling point than that of water under the same subatmospheric pressure, comprising mixing said residues with an aqueous liquid, continuously providing said mixture with a large surface area, maintaining said mixture, while under subatmospheric pressure, at a temperature between the boiling points of the solvent and water at the pressure employed to evaporate at least a portion of said solvent, and separating at least a portion of said mixture into an aqueous liquid phase containing water-wetted residues and a phase containing solvent-wetted residues.

2. A method as claimed in claim 1 wherein the vegetable residues are derived from the solvent extraction of oil from comminuted oil bearing vegetable materials.

3. A method as claimed in claim 1 wherein a portion of the partially desolventized mixture is recycled to the evaporating step for further evaporation of solvent therefrom.

35. 4. A method as claimed in claim 1 wherein the aqueous liquid is an aqueous alkaline solution.

5. A method as claimed in claim 1 wherein the mixture is sprayed to provide the large surface area.

40. 6. A method as claimed in claim 1 wherein the separation of the mixture is carried out at subatmospheric pressure for further evaporation of solvent.

7. A method as claimed in claim 1 and further 45 comprising removing the water-wetted residues from the separated aqueous phase.

8. A continuous method for treating vegetable residues wetted with a substantially water-insoluble organic solvent having a lower boiling point than that of water under the same subatmospheric pressure, comprising mixing said residues with an aqueous liquid, heating said mixture to a temperature not higher than about 60° C. while under subatmospheric pressure to evaporation at least a portion of said solvent, recycling a portion of said partially desolventized mixture to the evaporation step for further evaporation of solvent, collecting the remaining portion of the at least partially desolventized mixture, separating said collected mixture into an aqueous phase containing water-wetted residues and a phase containing solvent-wetted residues and some aqueous liquid, recycling said last mentioned phase to the evaporation step for further removal of solvent and withdrawing said aqueous phase.

9. A continuous method for treating vegetable residues wetted with a substantially water-insoluble organic solvent having a lower boiling point than that of water under the same subatmospheric pressure, comprising mixing said residues with an aqueous liquid, directing said mixture onto a pool of accumulated mixture while being maintained at a temperature not higher than about 60° C. and at subatmospheric pres-

sure to evaporate at least a portion of said solvent, recycling a portion of said partially desolvantized mixture to the evaporation step for further evaporation of solvent, collecting the remaining portion of the at least partially desolvantized mixture, separating said collected mixture into an aqueous phase containing water-wetted residues and a phase containing solvent-wetted residues and some aqueous liquid, recycling said last mentioned phase to the evaporation step for further removal of solvent and withdrawing said aqueous phase.

10. A method as claimed in claim 9 and further comprising treating the aqueous phase to separate an aqueous liquid from the solids.

11. A continuous method for treating vegetable residues wetted with a substantially water insoluble organic solvent having a lower boiling point than that of water under the same sub-atmospheric pressure, comprising mixing said residues with an aqueous alkaline solution, spraying said mixture into the top of a desolvantizing vessel maintained at a temperature not higher than 60° C. and at a subatmospheric pressure of about 28 inches, splashing said sprayed mixture onto a pool of accumulated mixture at the bottom of said vessel, withdrawing solvent vapors

5 from said vessel, withdrawing a mixture of alkaline solution, water-wetted residues and solvent-wetted residues from the bottom of said vessel, recycling a portion of said last mentioned mixture to said spraying step, introducing the remainder of said last mentioned mixture into a settling tank to separate an aqueous phase containing water-wetted residues from a phase containing the solvent-wetted residues and some alkaline liquid, recycling said last-mentioned phase to said spraying step for further evaporation of solvent and withdrawing said aqueous phase from said separator.
